Inventor:
Isaac V. Holmes

ISAAC V. HOLMES, OF NEW YORK, N. Y.

Letters Patent No. 86,305, dated January 26, 1869.

IMPROVED METALLIC LATHING

The Schedule referred to in these Letters Patent and making part of the same.

To all whom it may concern:

Be it known that I, ISAAC V. HOLMES, of the city of New York, in the county of New York, and in the State of New York, have invented a new and improved Metallic Stud for Fire-Proof Walls; and I do hereby declare that the following is a full and exact description thereof, reference being had to the accompanying drawings, and to the letters of reference marked thereon.

The nature of my invention consists in constructing studs of iron, or other suitable metal, to be used in the construction of walls of houses, and other like structures, in such form that metallic lath may be easily fastened to them, without bolts, nails, screws, or rivets, and may, when so fastened to them, materially add to their stiffness and strength, and thus secure a saving in the material of which they are constructed.

To enable others skilled in the art to make and use my invention, I will proceed to describe its construction and operation.

I construct my studs of iron, or other suitable metal, and of such thickness as may afford them sufficient strength, and of such width as will afford the desired thickness to the wall in any given case, the thin edges being presented to the laths and plaster, thus affording stiffness and strength to resist pressure against the face of the wall when made.

The studs are constructed in three different forms.

Figures 1, 2, and 3, respectively represent side views of three different forms of studs, and of lath fastened upon them.

Figure 4 is a front elevation, showing the lath in position and upon them.

Figure 5 is a perspective view of the studs and laths in position, figs. 1, 2, and 3, the variations in form being made to suit as many peculiar modes of fastening metallic lath upon them.

The general form of such laths as these studs are intended to be used with, is shown by the red lines and letters *e e e*, in fig. 3, where end views are presented of them, showing in what form the sheet-metal is bent in constructing them, while a front view of their faces, when in position in the studs, is shown in fig. 4, by the letters *e e*.

The stud A, fig. 1, has recesses for the laths cut away from it of the width of the laths, and of a little greater depth than the thickness of the sheet-metal of which they are formed, and these recesses are made just as far apart as it is desired to have the laths on the stud, and a projection of the material of the stud is left between adjacent recesses, as *f*.

Fig. 1. The bent back edges of the lath, of a width equal to the thickness of the stud, are cut away and removed, so that the back of the body of the lath will

fit up against the edge of the stud in the recess, then the back of the lath is placed flat upon the recess; and by the use of any suitable caulking-tool, the metal of the projection *f* may be beaten out and riveted upon the corners of adjacent laths, as at *g g*, and such corners are thus made fast to the stud.

Of course these projections and recesses in a row of studs should be in line.

In fig. 2, B represents a stud of a different form.

Here the variation is caused merely by making the recesses *C* deeper, and the projection *F* proportionately longer, and the seating of the lath in a different manner, and not a part of the lath cut away, but it is placed in the recess, and forced with its edges against the back of the recess, until these edges, which were formed at right angles to the face of the lath, are bent or curved into a direction parallel to the face, as shown by the red lines in *B*, and the faces of the lath are a little within the line of the projections *f f f*, and then the metal of these projections is riveted over, as at *g g*, as in fig. 1.

C, in fig. 3, represents a stud of still a different form from either of the other two.

Here the stud is formed with narrow slits *c c c*, at proper and regular distances apart, and deep enough to receive the whole of the bent back edges of the lath, and, by the cutting of these slits, the projections *f f f* are left to stand out between the edges of adjacent lath, and the edges being placed within the slits, the edges of the projections are riveted over, as shown in *C*, fig. 5, *g g*, just as the same thing was done in figs. 1 and 2.

These fastenings of the lath to the studs, thus severally made, and at short and regular intervals along their whole length, greatly stiffen and strengthen the studs, and prevent their bending laterally, so that they may be made and used much lighter and thinner than they might be, but for such fastenings, and a saving of metal in the result.

The ends of the studs are made with their ends to turn over in flanges, for the purpose of fastening them to the floor and ceiling when in position.

What I claim, and desire to secure by Letters Patent, is—

The mode of fastening, hereinbefore described, metallic laths, of any suitable form, upon metallic studs, when formed with recesses, or slits, by beating or heading the corners of the recesses or slits in the studs down over the edges of the laths, substantially as described

ISAAC V. HOLMES.
